UNITED STATES PATENT OFFICE.

GERTRUDE STRICKER, OF KANSAS CITY, MISSOURI.

GARMENT-HOOK.

No. 796,469.

Specification of Letters Patent.

Patented Aug. 8, 1905.

Application filed April 24, 1905. Serial No. 267,175.

To all whom it may concern:

Be it known that I, GERTRUDE STRICKER, a citizen of the United States, residing at Kansas City, in the county of Jackson and State of Missouri, have invented certain new and useful Improvements in Garment-Hooks, of which the following is a specification.

My present invention is an improvement over the devices secured by me in United States Letters Patent No. 755,411, issued March 22, 1904, for improvements in garment-fasteners, comprising fastening devices permanently secured to strips of braid or tape, said braid being adapted to be secured to a garment, and thereby dispenses with the use of ordinary hooks and eyes requiring the separate attachment of each end thereof.

The advantages possessed by the present invention over the one disclosed in the above-mentioned patent are:

First. The length of the fastening devices is considerably reduced. Hence less material will be required in their manufacture and they may be secured to narrower strips of braid or tape.

Second. The devices contain fewer bends and angles. Consequently they may be produced with a more simple and inexpensive machine in less time than the others.

Third. The hook is formed in such a manner that it protects the braid to which it is secured from wear when the eye is being hooked or unhooked.

The invention consists in the novel construction and combination of parts described and claimed, and in order that it may be fully understood reference will now be made to the accompanying drawings, in which—

Figure 1 represents an enlarged front elevation of two strips of braid provided with my fastening devices. Fig. 2 is a rear elevation of same. Fig. 3 is a side elevation of one of the eyes employed in carrying out the invention. Fig. 4 is a side elevation of my improved hook. Fig. 5 is an inverted plan view of the eye. Fig. 6 is an inverted plan view of the hook. Fig. 7 is an enlarged sectional view taken on line A B of Fig. 1. Fig. 8 is a perspective view of a modified form of eye.

Referring now to the drawings, wherein like numbers indicate similar parts throughout the several views, 9 designates a strip of

braid of any suitable material provided at regular intervals with my improved hooks, each of which is formed of a single piece of wire bent upon itself at the center. Said central portion is curved to form a bill 4, communicating at its rear end with a forwardly-extending shank 6. 5 designates a pair of rearwardly-diverging arms communicating at their forward ends with the shank and at their rear ends with underlying clamping-arms 7, terminating in inwardly-turned lugs 11. By referring to Fig. 7 it will be seen that shank 6 and arms 5 and 7 snugly engage the opposite sides of the braid, and thus prevent the hook from shifting thereon, the inwardly-bent lugs 11 assisting said shank and arms in reliably securing the hook to the braid. 8 designates another strip of braid similar to strip 9 and provided with a series of eyes arranged the same distance apart as the hooks, which latter they are adapted to engage, as shown in Fig. 1. Each eye is formed from a single piece of wire bent at its central portion to form a loop 2, the rear ends of which communicate with outwardly-extending shoulders 12.

Shoulders 12 communicate with a pair of rearwardly-extending parallel arms 1, communicating at their rear ends with underlying clamping-arms 3, which latter terminate at their forward ends in inwardly-turned lugs 10. By referring to Figs. 2 and 7 it will be seen that arms 1 extend through the braid at their point of juncture with shoulders 12, which prevent the eye from shifting backwardly, while the curved portions, formed by the juncture of said arms with the clamping-arms 3, prevent said eye from shifting forwardly on its strip of braid, lugs 10 assisting said shoulders and arms in reliably securing the eye in position.

In practice the eyes are arranged with their loops projecting beyond the edge of braid 8, so they may be conveniently engaged by the hooks, the bills of which latter terminate in slightly-flaring portions 13 for the easy entrance of loops 2, the latter being reliably held from becoming accidentally unfastened from said hooks by curved portions 14 of the bills and arms 5.

By referring to Fig. 7 it will be seen that arms 5 are interposed between the braid and the bills. Consequently when the eyes are se-

cured to or removed from the hooks they will rub against said arms instead of the braid. Hence the latter will be protected from wear at these points.

The hooks herein described are reduced in length to the length of their bills. Hence they may be secured to a much narrower strip of braid than the hooks disclosed in my patent above referred to. This advantage enlarges their field of usefulness and renders their employment more economical.

Referring now to the modified form of eye shown in Fig. 8, 2^a designates the loop, 1^a designates the arms communicating with the rear terminals of said loop, and 3^a designates the clamping-arms communicating with the rear ends of arms 1^a, which latter they underly and terminate in inwardly-extending lugs 10^a. Less material is required in the manufacture of this style of eye, as shoulders 12 are dispensed with.

The hooks and eyes are preferably secured to the braid in a permanent manner by a machine built expressly for the purpose, and when it is desired to place them upon a garment the braid is secured by sewing. Thus it will be understood a large number of hooks and eyes can be quickly fastened in this manner. Furthermore, the braid reinforces the garment and evenly distributes the strain produced thereon by the hooks and eyes, so that injury to the fabric is practically avoided.

The eyes and hooks may be attached to braid of any suitable length or width.

I am aware that other modifications than that shown may be made without departing from the spirit or sacrificing any of the advantages of the device, and therefore I reserve the right to make such changes and alterations as fall within the scope and spirit of the invention.

I claim—

1. In a device of the character described, the combination with a braid having eyes permanently secured thereto; of a second braid, a series of hooks permanently secured thereto, each hook being formed of a single length of wire and bent to form a bill, a forwardly-extending shank communicating with the rear portion of said bill, and rearwardly-extending arms communicating with the forward portions of the shank, said shank being arranged at one side of the braid, and the bill and arms being arranged at the opposite side of said braid with the arms between the braid and bill.

2. In a device of the character described, the combination with a braid having eyes permanently secured thereto; of a second braid, a series of hooks permanently secured thereto, each hook being formed of a single length of wire and bent to form a bill, a forwardly-ex-

tending shank communicating with the rear portion of said bill, rearwardly-extending arms communicating with the forward portion of the shank, forwardly-extending clamping-arms formed integral with the rear ends of the first-mentioned arms, said clamping-arms and the shank being arranged on one side of the braid and the bill, and the rearwardly-extending arms being arranged at the opposite side of said braid.

3. In a device of the character described, the combination with a braid having eyes permanently secured thereto, of a second braid, a series of hooks permanently secured thereto, each hook being formed of a single piece of wire and bent to form a bill, a forwardly-extending shank communicating with the rear portion of said bill, rearwardly-diverging arms communicating with the forward portion of the shank, forwardly-extending clamping-arms communicating with the rear portions of the diverging arms, and inwardly-turned lugs formed integral with the forward ends of said clamping-arms.

4. In a device of the character described, a hook formed of a single piece of wire and comprising a bill, a forwardly-extending shank communicating with the rear portion of said bill, rearwardly-diverging arms communicating with the forward portion of the shank, forwardly-extending clamping-arms formed integral with the rear portions of the diverging arms, and inwardly-extending lugs formed integral with the forward ends of said clamping-arms.

5. The combination with a braid having a wire projecting therefrom forming an eye, said eye consisting of a loop, a pair of rearwardly-extending arms, a pair of forwardly-extending clamping-arms communicating with the rear portions of said rearwardly-extending arms, and inwardly-turned lugs formed integral with the forward ends of said clamping-arms; of a second braid, a hook secured thereto formed of a single piece of wire, said hook consisting of a bill, a forwardly-extending shank communicating with the rear portion of said bill, and rearwardly-extending arms communicating with the forward portion of said shank, said arms being arranged between one side of the bill and the braid to form a sliding surface for the eye.

6. The combination with a braid having a wire projecting therefrom forming an eye, said eye comprising a loop, outwardly-extending shoulders formed integral with the ends of said loop, a pair of parallel arms extending rearwardly from said shoulders, a pair of clamping-arms extending forwardly from the rear portions of said parallel arms, and inwardly-extending lugs formed integral with the forward terminals of the clamping-arms;

of a second braid, a hook secured thereto consisting of a bill, a shank extending forwardly from the rear portion of said bill, arms extending rearwardly from the forward portion of the shank, said arms being arranged between the braid and the bill to provide a sliding surface for the eye.

In testimony whereof I affix my signature in the presence of two witnesses.

GERTRUDE STRICKER.
